(57) **CLAIM**

The ornamental design for a medical connector cover, as shown and described.

DESCRIPTION

FIG. 1 is a front, top, and right-side perspective view of a first embodiment of the design for a medical connector cover in an open configuration.

FIG. 2 is a rear, bottom, and left-side perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof.

FIG. 9 is a front, top, and right-side perspective view of a second embodiment of the design for a medical connector cover in a closed configuration.

FIG. 10 is a rear, bottom, and left-side perspective view thereof.

FIG. 11 is a front elevation view thereof.

FIG. 12 is a rear elevation view thereof.

FIG. 13 is a right side elevation view thereof.

FIG. 14 is a left side elevation view thereof.

FIG. 15 is a top plan view thereof; and,

FIG. 16 is a bottom plan view thereof.

The broken lines in the drawings show portions of the medical connector cover that form no part of the claimed design.
